UNITED STATES PATENT OFFICE.

LEWIS D. STARK AND JOHN R. SHEPPARD, OF DETROIT, MICHIGAN.

DESIGN FOR A BADGE OR BUTTON.

53,322.

Specification for Design.

Patented May 13, 1919.

Application filed January 27, 1919. Serial No. 273,493. Term of patent 7 years.

To all whom it may concern:

Be it known that we, LEWIS D. STARK and JOHN R. SHEPPARD, citizens, respectively, of the United States, residing at Detroit, county of Wayne, and State of Michigan, have invented a new, original, and ornamental Design for a Badge or Button, of which the following is a specification, reference being had to the accompanying drawing, forming a part thereof, in which—

The figure is a plan view of an ornamental badge or button showing our new design.

We claim:

The ornamental design for a badge or button substantially as shown.

LEWIS D. STARK.
JOHN R. SHEPPARD.
